D. D. SMITH

POWDER DUSTER

Filed July 24, 1923

Inventor

D. D. Smith

By D. Swift

Attorney

UNITED STATES PATENT OFFICE.

DANIEL D. SMITH, OF VALDOSTA, GEORGIA.

POWDER DUSTER.

Application filed July 24, 1923. Serial No. 653,481.

To all whom it may concern:

Be it known that I, DANIEL D. SMITH, a citizen of the United States, residing at Valdosta, in the county of Lowndes, State of Georgia, have invented a new and useful Powder Duster; and I do hereby declare the following to be a full, clear, and exact description of the invention, such as will enable others skilled in the art to which it applies to make and use the same.

The invention relates to powder dusters, and has for its object to provide a device of this character, which may be easily carried and operated by one hand of an operator, provided with means whereby powder may be intermittently dusted from the device as desired, thereby allowing a single operator to operate two machines at the same time if desired, for depositing powder on adjacent rows of plants. The device is particularly adapted for use in depositing powder on cotton plants for killing boll weevil, however it is to be understood that the device may be used in connection with various kinds of plants.

A further object is to provide a hand operated powder dusting device comprising a casing having its lower end open and a powder receiving bag disposed therein. The handle member for the casing is provided with lever and flexible connections with a weight in the bottom of the bag, which weight upon the operation of the device is intermittently raised and allowed to lower, thereby not only mixing the powder within the bag, but upon the lowering operation powder is dusted through the bag, and onto plants beneath the device.

A further object is to provide a wire mesh screen at the lower end of the casing for preventing portions of the plant from coming in contact with the bag. Also to provide a screen or shield extending entirely around the lower end of the casing for preventing powder as it is dusted from the device from being blown away from the plant.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawings:—

Figure 1 is a perspective view of the powder duster.

Figure 2 is a vertical transverse sectional view through the lower end of the duster.

Figure 3 is a detail perspective view of a portion of one of the arms of the U-shaped handle member, showing the lever pivoted thereto.

Referring to the drawing, the numeral 1 designates the rectangular shaped casing of the powder dusting machine and 2 a U-shaped handle member, which extends upwardly and has its arm 3 secured to the opposite sides of the casing 1. Although the casing 1 has been described as rectangular shaped, it may be round or any other shape desired. Disposed within the casing 1 is a powder receiving bag 4, which bag is formed from fabric and preferably from gauze, through which powder may easily pass upon a jolting of the bag 4. The bag 4 has its upper end secured to the casing 1 by means of removable cleats 5, therefore the bag may be easily removed when it is desired to replace the same with another bag. Secured in the lower end of the bag 4 is a weight 6, which may be of any shape desired, however for purposes of illustration it is shown as spherical shaped. During the operation of the device, the weight 6 is intermittently raised and allowed to drop for jolting the bag 4 and consequently causing powder within the bag 4 to sieve through the bag. Upon the upward movement of the weight 6, it will be seen that powder within the bag 4 will be agitated as the mixing operation takes place, and consequently the powder is thoroughly mixed during the operation of the device.

In operation the operator grasps the transverse portion 7 of the handle member and places his thumb on the member 8 of the vertically movable and guidable rod 9, forces said rod downwardly and then releases the same. The lower end of the rod 9 is pivotally connected at 10 to a rock lever 11, which rock lever has the transversely disposed portion 12 rockably mounted in one of the arms 3 of the U-shaped handle member, therefore it will be seen that after the lever 11 is formed from a single straight piece of material passed through the arm 3 and bent at 13, the lever 11 will be positively held on the arm 3 and pivot bolts eliminated, thereby reducing the working parts to a

minimum. Connected at 14 to the inner end of the lever 11 is a flexible member 15, which member extends downwardly into the bag 4 and is connected at 16 to the weight 6, consequently it will be seen that upon downward movement of the rod 9, the weight 6 will be raised, and when the rod 9 is released, said weight will drop, thereby imparting a jolting action on the fabric bag 4 and dusting powder therefrom. The lower end of the casing 1 is provided with a screen 17, which screen prevents parts of the plants, when the device is disposed thereover, from entering the casing 1, and interfering with the jolting operation. To prevent powder, as it is being dusted, from blowing away from the plants, the lower end of the casing 1 is provided with a shield 18, into which the upper ends of the plants may be received during a powder dusting operation.

From the above it will be seen that a hand operated powder dusting machine is provided, which machine is simple in construction and may be easily and quickly operated by one hand of the operator, and powder intermittently dusted therefrom by the intermittent raising and lowering of a weight carried by the powder bag. It will also be seen that the rod 9 is guided in its vertical movement by an eye 19 carried by one of the arms 3, consequently the finger engaging member 8 is held adjacent the hand engaging portion 7 of the handle member.

35 The invention having been set forth what is claimed as new and useful is:—

1. The combination with a powder dusting machine comprising a casing, a powder bag disposed therein, a weight carried by said bag, a handle member extending upwardly from said casing, of means for intermittently raising and dropping said weight, said means comprising a lever rock-

45 ably mounted on the handle member and having one of its arms disposed over the bag, a flexible member connecting said lever and said weight, a vertically movable rod connected to said lever, said rod terminating adjacent the upper end of the handle member.

50 2. The combination with a hand operated powder dusting machine comprising a casing, a powder bag disposed within the casing, a weight carried by said powder bag, means for intermittently moving the bag, of a screen carried by the lower end of the casing below the bag, and a windshield carried by the lower end of the casing and extending below said lower end of the casing.

55 3. A hand operated powder dusting machine comprising a casing having its lower end open, a screen carried by said lower end, a fabric powder receiving bag disposed within the casing, a weight carried by said bag, the upper end of said bag being detachably connected to the upper end of the casing, a U-shaped handle extending upwardly from said casing and having its arms secured to opposite sides of the casing, a rockable lever formed from a single piece of material and having a transverse portion rockably mounted in one of the arms of the handle member, a connection between said lever and the weight, and a vertically disposed operating rod connected to the rockable lever and having its upper end terminating adjacent the upper end of the handle member.

60 70 75 In testimony whereof I have signed my name to this specification in the presence of two subscribing witnesses.

80 DANIEL D. SMITH.
